UNITED STATES PATENT OFFICE.

FREDRICK KRETZSCHMAR, OF CHICAGO, ILLINOIS.

BASKET.

Application filed December 12, 1919, Serial No. 344,333. Renewed December 14, 1923.

To all whom it may concern:

Be it known that I, FREDRICK KRETZSCHMAR, a citizen of the United States, and a resident of Chicago, in the county of Cook and State of Illinois, have invented certain new and useful Improvements in Baskets, of which the following is a full, clear, and exact specification.

This invention relates to improvements in baskets provided with wood runners for reducing friction when pushing them, and particularly when large and heavy, over floors from one point to another and thereby avoiding the greater force otherwise required for lifting and carrying them.

For the purpose of securing these wood runners to the bottom of the basket, it has heretofore been the common practice to construct the runners of two pieces for the passage of the bottom wires between them and to clamp the bottom wires between these two pieces, at intervals of the runners, with bolts tightened by means of nuts on their inner ends and having heads counter-sunk at their outer ends in the runners, which in practice, however, is objectionable for the reason that the bolt heads soon become exposed from the frictional wearing down of the runners and as a result of which the bolt heads coming in contact with the floor not only increase its resistance to the runners, but that in a little while the floor is scratched, grooved and otherwise injured and defaced by the bolt heads.

In the construction of the baskets above referred to, it has also heretofore been the common practice to construct the foundation of the bottom of the basket of wires, separate and distinct from other wires, forming the foundation for the sides of the basket, and to secure the adjacent ends of the wires for the bottom and sides of the basket to longitudinal bars or sticks extending along the side edges of the basket.

The prime object of my invention broadly stated, is a basket the bottom foundation of which is formed of wires between which strips of willow, rattan, or other suitable material may be woven, provided with one or more runners, each of which is constructed in its entirety from a single piece of wood, or other suitable material, having perforations, through which the bottom wires may be threaded and preferably at a

point substantially removed from the bottom and wearing surfaces of the runners.

A further object of this invention is a basket having runners, each of which is formed of a single piece of material perforated at intervals for the passage of the bottom wires for the basket, which perforations are so arranged as to provide a means for bracing the runners of a basket against both a longitudinal and lateral movement, substantially promoting the rigidity and durability of the bottom of and also the basket as a whole, which perforations further provide a means by which it is both possible and practicable to have the bottom and side wires of a basket integrally connected.

With these ends in view, my invention finds embodiment in certain features of novelty in the construction, combination and arrangement of parts by which the said objects are attained, all as hereinafter fully described with reference to the accompanying drawings, and more particularly pointed out in the claims.

In said drawings,—

Fig. 1 is a plan view of a portion of the framework for a basket in which my invention finds its embodiment.

Fig. 2 is a transverse section taken on the line 2—2 of Fig. 1, and

Fig. 3 is a detail, partly in section, showing the means by which the bottom end bar of the basket is secured to and adjacent the ends of the runners, and the means by which the wires for the ends of the basket are separated and secured in their operative position.

In constructing the bottom and sides of the basket indicated in the drawings, runners 4, of which there may be any desired number, of a length corresponding with the size of the basket to be made, and rectangular in cross-section, are provided at intervals of the length with perforations 5, preferably located in a plane substantially above their wearing surfaces and are connected at their ends by an end bar 6, by means of screws and preferably by a wire nail 7 driven through the end bar 6 into the ends of the runners 4.

To the corners of the frame so formed are secured one or more posts 7', usually of rattan or willow, by means of wire nails

or binding wires connecting them with the end bar 6 or the runners, as may be, and at least with sufficient rigidity to enable the subsequently woven willow or rattan or other suitable strips to permanently lock them in their operative position to the runners, forming the bottom and side edges of the basket, as is commonly followed in the construction of baskets having a flat bottom.

10 Having thus constructed the bottom frame and the corner posts for the basket of my invention, wires 8 and 8^a, of sufficient length for the foundation of the bottom and sides of the basket, are threaded in pairs through the perforations in the runners 4 to form the bottom wires which are bent upwardly to form the foundation for the bottom 9 and longitudinal sides of the basket, the free ends of the upwardly extending wires being bent outwardly at 10, thence downwardly as at 11, inwardly as at 12, and upwardly as at 13, to provide an anchorage for strips of rattan or willow 14, interwoven for the construction of a substantially thick and strong rim 15 for the upper side edges of the basket, and also continuously therewith for both ends of the basket, as will be presently described.

15 Any number of runners 4 may be used, but, as shown in the drawings, there are three, two of which extend along the longitudinal side edges of the basket bottom.

20 Of these runners it is now to be observed that their opposing perforations 5 register transversely of the basket; that the wires 8 and 8^a in pairs are passed through a single perforation in the central runner and thence diverge in opposite directions to the side runners, whence they again diverge upwardly in the opposite direction to the rim of the basket; and that as a result of their divergence the wires 8 and 8^a respectively, pass through alternate perforations in the side runners and form a network of closely fitting diamondlike spaces which in the bottom of the basket adjacent the side runners are truncated and likewise in the rim, the diamond-shaped spaces of which, however, extend lengthwise at a right angle to those in the bottom.

25

With each pair of wires passing through the side and central runners and diverging from the former, as above described, they operate not only to support the runners, but as stay and tension chords, sustaining the runners against longitudinal movement in either direction from the force of blows directed against the ends of the basket and the force of the frictional resistance when shoving the basket over a floor and whereby the distortions of the bottom frame are prevented and its rigidity and durability as a whole correspondingly increased.

30 In this connection it is to be noted that the bend 11^a (see Fig. 2) between and con-

necting the bottom wires with the rim wires, provides for the slight longitudinal movement of the adjacent ends of the bottom wires in their perforations and against the yielding resistance of one or more strands 70 12^a and 13^a, at opposite sides of the wires for distributing throughout the length of the bottom wires and transversely of their frame the lateral compression of the frame due to force directed laterally therethrough. 75

Concerning this distribution of forces from impact against the bottom rim of the basket, it may be further observed that, filled as are the spaces between and surrounding the wires of both the bottom and rim with closely interwoven strips of willow or rattan, the centering of forces tending to and frequently fracturing or breaking the woven fabric, is substantially and materially reduced, and this in a basket 80 85 that, to all intents and purposes, is as a whole a substantially rigid structure, the flexibility of which is confined almost in its entirety to the rim.

Having described my invention, what I claim as new and desire to secure by Letters Patent is:—

1. A woven rim basket provided with runners each constructed of a single piece perforated at intervals of their length, and 95 wires extending across the bottom of said basket passing in pairs through the perforations in said runners and woven rim.

2. A basket provided with runners and with a rim, wires for forming the bottom 100 and a woven rim therefor, constructed of one piece extending across the bottom of the basket from edge to edge thereof, and connecting the runners with the woven rim.

3. A basket provided with longitudinal runners constructed of a single piece, adjacent the side edges of the bottom, thereof, an intermediate similarly constructed runner, each of said runners being provided with perforations at intervals of their length, and a 105 pair of wires passing through perforations in each of said runners and thence diverging in opposite directions from the intermediate runner to the side runners.

4. A basket provided with longitudinal runners constructed of a single piece, located adjacent the side edges of the bottom thereof, an intermediate similarly constructed runner which said several runners are provided with perforations transversely therethrough at intervals of their length, and with a pair of wires passing through each of said perforations and diverging in opposite directions relative to said runners and to the rim of the basket. 115

5. A basket provided with runners each consisting of a single piece having perforations transversely therethrough for the passage of wires, a pair of wires passing through each of said perforations diverging 120 125 130

therefrom each of which pairs of wires extend upwardly into the rim of said basket and adapted for the weaving of strips of rattan and other suitable material between the wires of the several pairs.

6. A basket having single piece runners transversely perforated, provided with wires passing in pairs therethrough, which wires are bent upwardly at a point distant 10 from the outer runners and provide a space

between their upright portion and the sides of the outer runners substantially as and for the purpose described.

In witness whereof, I have hereunto set my hand and affixed my seal this 29th day 15 of November, A. D. 1919.
